CLAIM

The ornamental design for a watch body glass dome, as shown and described.

DESCRIPTION

FIG. 1 is a front perspective view of a watch body glass dome according to a first embodiment of our new design; FIG. 2 is a rear perspective view thereof;

FIG. 3 is a front plan view thereof;

FIG. 4 is a back plan view thereof;

FIG. 5 is a right side view thereof;

FIG. 6 is a left side view thereof;

FIG. 7 is a top plan view thereof;

FIG. 8 is a bottom plan view thereof;

FIG. 9 is a front perspective view of a watch body glass dome according to a second embodiment of our new design; FIG. 10 is a rear perspective view thereof;

FIG. 11 is a front plan view thereof;

FIG. 12 is a back plan view thereof;

FIG. 13 is a right side view thereof;

FIG. 14 is a left side view thereof;

FIG. 15 is a top plan view thereof;

FIG. 16 is a bottom plan view thereof;

FIG. 17 is a front perspective view of a watch body glass dome according to a third embodiment of our new design showing an exploded view of a front and rear domes; FIG. 18 is a rear perspective view thereof;

FIG. 19 is a front plan view thereof;

FIG. 20 is a back plan view thereof;

FIG. 21 is a right side view thereof;

FIG. 22 is a left side view thereof;

FIG. 23 is a top plan view thereof; and,

FIG. 24 is a bottom plan view thereof.

The broken lines (including, for example, the buttons, connection ports, and the mask pattern feature in certain embodiments) illustrate environmental structure and form no part of the claimed design.
